UNITED STATES PATENT OFFICE.

JOHN WILLIS GARROW, OF COPPER CLIFF, ONTARIO, CANADA, ASSIGNEE OF ONE-THIRD TO JAMES D. CUMMING AND ONE-THIRD TO GEORGE E. CRAIG, BOTH OF COPPER CLIFF, ONTARIO, CANADA.

GRINDING-MILL.

1,295,726.

Specification of Letters Patent. Patented Feb. 25, 1919.

Application filed May 17, 1917. Serial No. 169,285.

To all whom it may concern:

Be it known that I, JOHN WILLIS GARROW, of the town of Copper Cliff, in the District of Sudbury, in the Province of Ontario, Canada, have invented certain new and useful Improvements in Grinding-Mills, of which the following is the specification.

My invention relates to improvements in grinding mills and the object of the invention is to devise a mill, which will produce an increased grinding of the material and a positive discharge of the ground material and it consists essentially of a grinding drum having tapered heads having inclined 15 opposing parallel inner ends having circular inlet and discharge orifices arranged at right angles to the axis of rotation, each head tapering from the circular end into an ovoid opposite inner end as hereinafter more 20 particularly explained by the following specification.

Figure 1. is a general perspective view of a mill.

Fig. 2. is an enlarged longitudinal section 25 through the mixing drum.

Fig. 3. is a sectional view of an interchangeable discharge mouth of different diameter to that shown in Fig. 2.

Fig. 4. is a view of the discharge end of 30 the drum.

Fig. 5. is a sectional view on line $x-y$ of Fig. 2.

Fig. 6. is a longitudinal section through an alternative form of mixing drum.

Fig. 7. shows another modification.

In Figs. 1 and 2, 1 indicates the mixing drum which comprises a central portion 2 having the peripheral wall thereof parallel with the axis around which the drum is rotated. The ends 2^x and 2^y of such peripheral portion 2 are inclined to the axis of rotation, such axis being indicated by dotted line A—A Fig. 2 and the heads 3 and 4 having their inner ends correspondingly inclined to the ends 2^x and 2^y, the heads being either formed integral with such central portion or suitably secured thereto. In the drawing the heads 3 and 4 are shown integral with the central portion 2. The heads 3 and 4 are tapered, the head 3 being provided with an inlet orifice 3^x set at right angles to the axis of rotation A—A and the head 4 with a discharge opening 5 around which is secured an annular flange 6. 7 indicates a discharge

mouth which is tapered in form provided at 55 its inner end with a flange 7^x adapted to be secured to the flange 6. By this means the discharge mouth 7 is rendered detachable from the drum so that it can be interchanged with discharge mouths of less internal diameter such as shown in Fig. 3. By this means it will be seen that the grade formed between the lower peripheral portion of the inlet orifice 3 and the lower peripheral portion of the discharge mouth 7 may be varied 60 65 in order to suit requirements and to increase or decrease the rate of discharge. The steeper the grade between the inlet 3 and the discharge mouth 7 the greater will be the speed of the discharge through the outlet 70 mouth 7, and the less finely ground will be the discharged product.

It will thus be seen that a simple means is provided whereby the diameter of the outlet is varied for decreasing or increasing the 75 grade from the inlet to the outlet of the mill. In other mills this result is attained by tilting the mill bodily keeping the diameter of the outer end constant. By this means it will be readily understood that great inconvenience would be rendered owing to the necessity of re-adjusting the line shafting, 80 motor or other driving means in order that it may be accommodated to the new position of the grinding mill so that it can align up 85 with the new axis of the mill. In the applicant's construction the axis of the mill need not be disturbed and, therefore, the necessity for adjusting the line shafting is obviated.

By the above described construction of 90 drum an increased activity and washing action is imparted to the balls indicated by the numeral 8, which are employed in this class of mill, this washing action being produced by the inclination of the junction of the two 95 cones with the cylindrical section or with each other as in Fig. 7 where the washing action is produced by the inclination toward the junction of the two tapering ends. By this construction the material is not only 100 thoroughly ground by a continued reciprocating action and the rolling action imparted to the grinding media by the revolution of the shell but the finer material is fed gradually toward the discharge end.

In a mill of this kind, due to the agitation and irregular motion caused by the reciprocating action of the balls and ma-

material, I do not claim a regular and automatic sorting or separation of the coarse and fine material, further than that as the material passes through the mill it will be acted upon in its progress through the grinding media more or less in proportion to the distance traveled. For this reason it may be expected that material reaching the outlet end will be more or less finely ground. As such finer material is carried to the discharge end it is gradually fed through the mouth 7, the speed at which such discharge is produced being regulated by the internal diameter of the mouth piece 7. If it is desired to decrease the speed of the discharge or alter the fineness of the discharged product all that it is necessary to do is to remove the mouth 7 and secure a similar mouth of smaller diameter in place. It will be understood that while this washing action is reciprocating yet the material carried to the outlet is discharged in part and cannot return at the return movement. In order to fill this space a constant progression of the finely ground particles toward the outlet of the mill is maintained. This action is much more positive than the force acting on particles in other conical mills which consists of the resultant of the centrifugal force and the force of gravity due to the inclination of the mill. This resultant in other mills has been found to be very slight and the discharge action very sluggish particularly when grinding without the addition of water or other liquid.

In both forms shown in Figs. 1, 2 and 6 and 7 an annular gear 16 is secured to the central cylindrical portion, the drum being suitably provided with annular ways 17 and 18 (see Fig. 1) which are mounted on rollers 19. Although I have shown this means of mounting the drum it will, of course, be understood that any other means may be provided. In the form shown in Fig. 1 the drum is rotated by means of a pinion 20 mounted upon a suitable shaft 21 in mesh with the annular gear 16.

In Fig. 6, I have shown an alternative form in which the construction of inlet and outlet are modified.

In Fig. 7, I have shown a form of drum with the central cylindrical portion dispensed with and comprising two tapered portions 22 and 23 inclined at 24 forming their line of junction to the axis of rotation.

In grinding certain materials that are not thoroughly dried or are of a sticky or plastic nature, there is a tendency for the finely ground material to accumulate on the shell near the outlet end, where the balls or other grinding media are smaller and where the material is not so violently acted upon. In mills with regular conical ends such material accumulates in a gradually increasing crust or coating on the outlet cone until

the balls are kept away from the shell and cease to grind efficiently, finally allowing the outlet of the mill to close up entirely.

As soon as these small balls no longer touch the shell plates on which they are intended to roll, they only tend to consolidate the incrustation by their tamping action on the moist or plastic fine material.

It is found that if a groove be cut lengthwise of the mill in the incrustation, that the balls come again in contact with the shell plates on the outlet end and if further moist material is not added, that they tend to scour this groove wider, and the arch being weakened the incrustation breaks and falls away from the shell.

The necessity of cutting this groove and the delay in operation due to this incrustation and its removal in mills with regular conical ends is a source of trouble and inconvenience in the grinding of the above mentioned class of material.

This harmful result is overcome in the grinding mill, described by the peculiar construction of the tapering ends of the mill. It will be seen from Fig. 4 that a section of the tapering end, normal to the axis, at the junction with the removable discharge nozzle, is a true circle. At the section $\alpha-y$ and at any other point on the tapering end except at section $x'-y'$, a section normal to the axis of the mill is roughly egg-shaped, with a series of different lengths at different points on the periphery.

As the mill revolves the pressure between the grinding plates attached to the shell and a selected ball varies with the momentum of the ball at the point of contact. This momentum varies as the length of the arm from the axis of the mill to the center of the ball, and since the ball remains in contact with an ovoid section of the shell in its revolution, this ball is acted upon in a cycle of increasing and diminishing momentum and therefore an increasing and diminishing intensity of grinding action takes place in each revolution.

This relative increase and decrease in grinding action at the different points on the periphery of a normal section in conjunction with the washing action imparted to the balls prevent the formation of an incrustation by keeping its arch broken at one or more points on the periphery of the tapering ends, avoiding the relays and inconvenience experienced in mills with regular conical ends, when "dry grinding" the above materials.

It has been found that in order to achieve the results claimed for the mill, such as, increased agitation of the balls, forward propelling action of the material being ground, prevention of the formation of an incrustation, etc., that it is necessary to have a minimum angle of offset of about 3 degrees.

This angle of offset may be described as the angle between a normal to the central axis of the mill and the line of intersection between the tapering ends of the mill at their junction, or if a cylindrical center section be used, the line of junction between the cylindrical center section and the tapering end.

From this description it will be seen that

- 10 I have devised a grinding mill in which an increased reciprocating or washing action is produced so as to thoroughly grind the material which may be fed into the mill either in a dry or wet state, in which simple means is provided for regulating the speed of the discharge of the material from the drum whereby the degree of fineness to which the material is reduced is regulated, such regulation being attained without disturbing the position of the drum so that the alinement of the axis of rotation and the line shafting always remain constant and thereby obviates any necessity for disturbing the line shafting and driving mechanism in order to produce the above adjustment and in which the peculiar shape of the tapering ends of the drum prevent the formation of incrustations of damp and sticky material.

- 25 30 The advantages from having the ends of the main body portion inclined to the axis of rotation of the drum are:

1. Increased amount of grinding action.

- 35 This is due to the combined rotary and reciprocating motion giving the maximum activity and relative motion to the balls or other grinding media between the balls and the outer shell.

2. Accelerated discharge.

This is caused by the reciprocating action set up in the material that causes any material near the discharge nozzle to be discharged in the forward surge of the material and balls set up by the inclination of the ends of the mill to the central cylindrical portion.

3. The prevention of accretions on the walls of the mill when grinding damp or sticky material.

This action is obtained by the combination of the ovoidal section of the tapered ends or particularly the discharge end where the material is finer and the reciprocating motion set up by the inclination of these tapered ends to the central cylindrical portion of the mill, and is also due to the fact that for any given inclination of the grade of the material the discharge nozzle diameter will be greater than in a mill where the axis of the mill is tilted to give this inclination to the grade line of the material, this larger diameter of the discharge nozzle helping to prevent the arching effect necessary to form accretions.

What I claim as my invention is:

In a grinding mill, a grinding drum comprising a central cylindrical portion whose axis is parallel and coincident with the axis of rotation and having its inner periphery concentric therewith and the planes of its ends inclined from the perpendicular to this axis and parallel and tapered heads secured to such inclined ends having respectively inlet and discharge mouths formed thereon.
